Primary Examiner — Susan Bennett Hattan*Assistant Examiner* — Marie Fast Horse(74) *Attorney, Agent, or Firm* — Malloy & Malloy, P.L.**CLAIM**

The ornamental design for a suspension packaging, as shown and described.

DESCRIPTION

FIG. 1 is a front perspective view illustrating my design for a suspension packaging;

FIG. 2 is a front elevation view thereof;

FIG. 3 is a right side view thereof;

FIG. 4 is a top view thereof;

FIG. 5 is a left side view thereof;

FIG. 6 is a bottom view thereof; and,

FIG. 7 is a rear elevation view thereof.

Included in the claim are the evenly spaced broken lines shown in FIGS. 1, 2 and 7 which depict straight fold lines.
